UNITED STATES PATENT OFFICE.

NEIL T. ALBRIGHT, OF KOKOMO, INDIANA, ASSIGNOR TO KOKOMO AUTOMOTIVE MFG. CO., OF KOKOMO, INDIANA, A CORPORATION.

DESIGN FOR A FACEPLATE FOR SIGNAL LAMP.

Application filed March 17, 1924. Serial No. 8,958. Term of patent 3½ years.

To all whom it may concern:

Be it known that I, NEIL T. ALBRIGHT, a citizen of the United States of America, residing at the city of Kokomo, county of Howard, and State of Indiana, have invented a new, original, and ornamental Design for Faceplate for Signal Lamp, of which the following is a specification, reference being had to the accompanying drawing, forming part thereof.

The figure is a front elevation of a faceplate for signal lamp, showing my new design.

I claim:

The ornamental design for a faceplate for signal lamp, as shown.

NEIL T. ALBRIGHT.
